(57) **CLAIM**

The ornamental design for a foldable weight bench as shown and described.

DESCRIPTION

FIG. 1 is a perspective view of a foldable weight bench showing my new design;

FIG. 2 is another perspective view thereof;

FIG. 3 is a front view thereof;

FIG. 4 is a back view thereof;

FIG. 5 is a left view thereof;

FIG. 6 is a right view thereof;

FIG. 7 is a top plan view thereof;

FIG. 8 is a bottom plan view thereof; and,

FIG. 9 is a partial enlarged view of portion 9 in FIG. 1. The broken lines depict portions of the foldable weight bench and form no part of the claimed design.

The dot dash line is included for the purpose of illustrating the bounds of the enlarged view and forms no part of the claimed design.
